UNITED STATES PATENT OFFICE.

MOSES SILVERMAN, OF NEW YORK, N. Y., ASSIGNOR TO THE KURSHEEDT MANUFACTURING COMPANY, OF NEW YORK, N. Y., A CORPORATION OF NEW YORK.

DESIGN FOR TRIMMING.

SPECIFICATION forming part of Design No. 35,228, dated October 22, 1901.

Application filed September 7, 1901. Serial No. 74,704. Term of patent 3½ years.

● *To all whom it may concern:*

Be it known that I, MOSES SILVERMAN, a citizen of the United States, residing in the borough of Manhattan, city, county, and State 5 of New York, have invented and produced a new and useful Design for Trimming, of which the following is a specification.

The accompanying drawings show a trimming exhibiting my new design.

10 Figure 1 is a plan view, and Fig. 2 a cross-section on the line 2 2 of Fig. 1.

My new design consists in a trimming of the particular shape and ornamentation shown in the drawings, to wit:

15 A is a longitudinal rib located between the parallel edges B B of the trimming and itself

parallel thereto. This longitudinal rib is formed at intervals with enlargements C, approximately of dumb-bell shape. Between the edges B and the rib A are located narrow 20 longitudinal ribs D, of which those adjacent to the edges are straight, while those adjacent to the rib A follow the outline thereof—that is, such narrow ribs D are curved or bulged outward adjacent to the enlargements C. 25

I claim—

The design for a trimming, substantially as shown and described.

MOSES SILVERMAN.
